[57] CLAIM

The ornamental design for a chemical feeding syringe pump, as shown and described.

DESCRIPTION

FIG. 1 is a front, top, right side perspective view of a chemical feeding syringe pump showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

FIG. 1

FIG. 2

FIG.3

FIG.4

FIG.5

FIG.6

FIG.7
